No. 630,653.

Patented Aug. 8, 1899.

C. A. BURNHAM.
WIRE FENCE DEVICE.

(Application filed Apr. 21, 1899.)

(No Model.)

B Cornelius A. Burnham,
By
Collamer & Co., Attorneys.

UNITED STATES PATENT OFFICE.

CORNELIUS A. BURNHAM, OF HOLLY, MICHIGAN.

WIRE-FENCE DEVICE.

SPECIFICATION forming part of Letters Patent No. 630,653, dated August 8, 1899.

Application filed April 21, 1899. Serial No. 713,987. (No model.)

To all whom it may concern:

Be it known that I, CORNELIUS A. BURNHAM, a citizen of the United States, and a resident of Holly, Oakland county, State of Michigan, have invented certain new and useful Improvements in Wire-Fence Machines; and my preferred manner of carrying out the invention is set forth in the following full, clear, and exact description, terminating with 10 claims particularly specifying the novelty.

This invention relates to the art of wire-working, and more especially to the act thereunder known as "joining;" and the object of the same is to produce a device for applying 15 stays to wire fences or stringers which shall be an improvement over Patent No. 568,660, granted to me on September 29, 1896.

To this end the invention consists, essentially, in the use of a spacer which is rotatory 20 in such manner as to disengage its slotted studs from the oblique parts of the stay and in a carrier for said stay-wire; and it consists, specifically, in certain details for carrying out the general idea and for effecting improvements 25 on the patent aforesaid, all as herein-after described and claimed and as illustrated in the accompanying drawings, wherein—

Figure 1 is an elevation of a section of fencing, showing the fence-machine as applied 30 thereto in the act of interlocking the stays. Fig. 2 is a plan view of the same. Fig. 3 is a perspective detail of the carrier for the stay-wire, showing in dotted lines how its tongue can be disengaged from the last coil thereof. 35 Fig. 4 is an obverse view of the same. Fig. 5 is a section through the drum, the shank, the handle, and the tongue and pivot. Fig. 6 is a perspective detail showing the spacer in section and means for locking the stringer-wire thereto.

Referring to the said drawings, the letters A C designate fence-posts connected by stringer-wires B, which are in turn temporarily supported by staples until removed for 45 machine to pass, when staples are replaced.

D designates a spacer which is an upright bar, as of wood or the like, and which has a crank E journaled therethrough at a proper point to frictionally engage the upper 50 stringer-wire.

F designates a series of studs attached to the spacer and having at opposite edges of

the latter oblique slotted heads f and eyes f' on their bodies, and through said eyes is adapted to be passed a vertical locking-pin 55 O to stand outside the stringer-wires and hold the same within said eyes.

K is the weaver-tool, which is of substantially U shape, with a recess M at the end of one arm and a slot N at the end of its other arm. 60

L designates a handle whose inner end I is journaled through the spacer-body D from the rear.

P designates the drum of a carrier, which has a metal hub Q, mounted on a bolt or pin 65 R, projecting from the shank S of a handle T, which drum preferably has a flange P' at that end next the shank. U is an eye at one end of the shank, and V is a tongue pivoted at W to the shank near its other end, so that 70 one extremity of the tongue engages the last coil of the stay-wire around said drum, while the other extremity of said tongue stands in a notch X within the handle. By this means it will be clear that a stay-wire in coiled condition can be passed onto the drum and one 75 end led through the eye U. Then the tongue V can be turned on its pivot so that one extremity touches the drum and holds the last coil of said stay-wire next its flange P', and the other end of the tongue at that time falls into the notch X. When desired, the outer 80 end of this tongue V can be raised out of the notch X and the whole turned upon the pivot W, so as to disengage its inner end from the 85 stay-wire and to permit the application of a new stay-wire in coil form to the drum.

All parts are of the desired sizes, shapes, proportions, and materials, and the studs F are located upon the spacer-body in any manner and distance apart that is preferred. 90

In the use of this machine the stringer-wires are attached to the posts and supported at proper intervals by the intermediate posts, the wires being drawn to a proper tension. 95 The spacer is then brought into use, when its eyes f' will stand astride the stringer-wires, the crank E is turned upward, so as to bind the uppermost stringer to the stud F, and the pin O is dropped into place at one end of the 100 studs to hold the stringer-wires therein. A stay in coil form is then applied to the drum P of the carrier, one end led through the eye U, and the tongue V turned so that its shorter

end shall engage the last coil. The outer end of this stay-wire is then passed upward through the slotted head *f* of the uppermost stud *F*, and the carrier is deflected to the right and 5 upward until the stay is bent, as shown in Fig. 1. The weaver-tool is then applied with its end *N* embracing both the stringer and stay-wires and its end *M* passing between these wires, and its body is then rotated several times around the upper stringer-wire, 10 carrying the carrier and coiled stay with it. The stay is then led obliquely from the right-hand end of this cable-twist down to and through the slotted head *f* of the stud *F* next below, and the operation of twisting the stay-wire is repeated, and so on until the entire stay-wire has been unreeled from the drum *P* and applied to the various stringer-wires. 15 A second stay-wire in coiled form is then applied to the carrier, the crank *E* loosened, the spacer moved about eighteen inches from the position at first occupied, and the operation is repeated, the staples in the intermediate posts *C* being removed as necessary. 20

25 One advantage of the present construction consists in the fact that the handle *L* is journaled at *I* through the spacer-body, and when it is desired to move the latter along the stringers and the crank *E* is opened for this purpose it is only necessary to turn the handle *L* upward to the position shown in dotted lines, then press it to the rear, thereby turning the entire spacer axially on the point between its eyes *f'* where the stringer-wires are 30 engaged and so as to disengage the slotted heads *f* from the oblique portions of the stay-wire last applied thereto, (which was not possible in my former patent,) and then move the entire spacer one space to the left and 35 swing it back into position for a new operation. This I consider an essential point of novelty, inasmuch as it facilitates the rapid working of the entire machine. Another feature of advantage herein is that the free end of 40 the stay-wire, which is being interlocked with each stringer and which formerly whipped about to the annoyance of the operator, is now conveniently coiled upon the drum *P* of the carrier, and yet the last-mentioned tool 45 is so constructed that the coiled stay thereon unwinds only as it is drawn therefrom and one convolution at a time.

I do not confine myself to the use of the specific form of weaver-tool herein described 50 and shown, as it is obvious that other devices may be used in substitution thereof.

What is claimed as new is—

1. In the machine herein described, an upright spacer, a series of studs attached thereto, means for pivotally connecting one end of 55 these studs with the stringer-wires, heads at the other ends of these studs having slots open at their front, and means for detachably preventing the turning of said spacer 60 on its pivot, as and for the purpose set forth.

2. In the machine herein described, an upright spacer, a series of studs attached thereto and having alined eyes at one edge of the spacer and slotted heads at the other, a locking-pin removably passing through said eyes 70 for pivotally supporting the spacer on the stringer-wires at one end of said studs, and a crank in the spacer adapted to engage one stringer-wire upon and near the opposite end of one of said studs, as and for the purpose 75 set forth.

3. In the machine herein described, an upright spacer, a series of studs attached thereto and having alined eyes at one edge of the spacer and slotted heads at the other, a locking-pin removably passing through said eyes 80 for pivotally supporting the spacer on the stringer-wires, and means for turning the spacer on said pivot, as and for the purpose 85 set forth.

4. In the machine herein described, an upright spacer, a series of studs attached thereto, means for pivotally connecting one end of these studs with the stringer-wires, heads at the other end of these studs having slots 90 open at their front, and a handle pivoted to the back of the spacer and adapted to be turned out at right angles thereto, as and for the purpose set forth.

5. In the machine herein described, a stay-carrier comprising a drum, a shank with an eye at one end and a handle at the other, and a pin or bolt on the shank passing through the drum and forming a pivot therefor at such point as to permit the eye to stand beyond the drum, as and for the purpose set forth. 95

6. The herein-described carrier for a coiled stay, the same comprising a drum having a flange at one end, a handle having a shank 105 secured to said flange, said handle being provided with a notch in its body, and a tongue pivoted to the handle with one end adapted to engage the convolution of the coil next said flange while the other end rests detachably in the notch, as and for the purpose set forth. 110

7. The herein-described carrier for a coiled stay, the same comprising a drum, a handle having a pivotal point for said drum and projecting beyond it where it carries an eye, said handle being provided with a notch in its body, and a tongue pivoted to the handle with one end adapted to engage the convolution of the coil next 115 said flange while the other end rests detachably in the notch, as and for the purpose set forth. 120

In testimony whereof I have hereunto subscribed my signature this the 11th day of April, A. D. 1899.

CORNELIUS A. BURNHAM.
